UNITED STATES PATENT OFFICE.

OSCAR P. WELKER AND JOSEPH F. WELKER, OF ST. LOUIS, MISSOURI.

FOLDING CRIB BED.

1,402,328.

Specification of Letters Patent.

Patented Jan. 3, 1922.

Application filed September 14, 1920. Serial No. 410,166.

To all whom it may concern:

Be it known that we, OSCAR P. WELKER and JOSEPH F. WELKER, citizens of the United States, residing at St. Louis, State 5 of Missouri, have invented certain new and useful Improvements in Folding Crib Beds, of which the following is a specification.

This invention relates to new and useful improvements in folding or collapsible cots 10 and beds, the primary object of the invention being to provide a reposing structure of this nature which may be readily collapsed or folded, whereby the same may be conveniently pushed beneath an ordinary 15 bed or may be folded to occupy the minimum amount of space.

Another object of the invention is to provide a device of the above nature including a supporting frame and a mattress supporting structure which is vertically movable 20 and capable of being arranged within the confines of the supporting frame when the device is in a collapsed position.

Another object of the invention is to provide improved means for securely retaining 25 the cot in an open position.

A still further object of the invention is to provide a crib having movable side members and means associated therewith for 30 locking or latching the side members in a position to enclose the occupant of the crib.

Still another object of the invention is to provide a collapsible crib including novel 35 means for hinging the side members whereby they may be moved into position from which they are capable of swinging outwardly and downwardly of the crib.

Still another object of the invention is to 40 provide a device of the above nature including a vertically movable mattress supporting structure and means for supporting the mattress structure when the same is arranged in a closed position.

Other objects and advantages of the invention will become apparent during the course of the following description.

In the accompanying drawings forming a 50 part of the application and wherein like numerals are employed to designate like parts throughout the several views.

Figure 1 is a side elevation of the invention.

Figure 2 is an end elevation of the same.

Figure 3 is a transverse section on the line 55 3-3 of Figure 1.

Figure 4 is a side elevation of the invention in a closed or collapsed position.

Figure 5 is a transverse section of the same taken on the line 5-5 of Figure 4. 60

Figure 6 is a longitudinal section of the collapsed crib taken on the line 6-6 of Figure 5.

Figure 7 is a detail perspective view of the corner of the crib, and 65

Figure 8 is an enlarged sectional detail of the means for hinging the side members to the frame of the cot or crib.

Referring now to the drawings wherein for the purpose of illustration is shown the 70 preferred embodiment of the invention, the supporting frame of the cot or crib consists of four posts or legs 9 forming integral parts of a pair of longitudinally extending spaced side rails 10. The legs 9 are braced by transversely extending brace rods 11 as clearly shown in Figure 2.

The supporting structure indicated in its entirety by the numeral 12 consists of a substantially rectangular frame in the present 80 instance the side and end rails 13 and 14 of which consists of L-shaped angle beams as more clearly shown in Figures 3 and 6. Rising from the rails of the mattress structure are vertical spaced posts 15 which support 85 in spaced relation to the rails of the mattress structure, a railing 16 extending entirely around the mattress structure.

It will of course be understood that the mattress supporting structure 12 is substantially smaller than the supporting frame and consequently the former may be disposed within the confines of the latter when the cot or crib is in a collapsed position. In order that the mattress structure may be moved 90 vertically a pair of L-shaped supporting members 17 are associated with each side of the cot. Each supporting member has the extremity of one arm thereof angularly disposed outwardly of the crib and journaled in 100 an opening in the longitudinally extending side rail 10 at the juncture thereof with the supporting leg 9. These members are adapted to swing inwardly toward each other and the other arm 18 of each member is provided 105 with an inwardly extending pin 18' for longitudinal sliding movement within a slot 19 provided in the side rail of the mattress supporting structure. It will of course be understood that a pair of these slots are provided in each side rail 13, one being arranged adjacent each end thereof. It will also be 110

apparent that the L-shaped supporting members 17 are disposed between the longitudinally extending rails 10 and their respective side rails 13 of the mattress supporting structure.

The means provided for retaining the mattress supporting structure in an open or elevated position as clearly as seen Figure 1, consists of a bar 20 pivoted between its ends as at 21, it being understood that a similar bar is pivoted to the outside of each side rail 13 of the mattress supporting structure. One end 22 of each bar is inclined upwardly and inwardly for abutment with the free end 15 of the arms 18 constituting a part of a supporting member 17. The bar 20 adjacent its opposite end is offset outwardly as at 23 whereby this end of the bar is arranged in spaced parallel relation to the side rail of 20 the mattress supporting structure whereby an auxiliary bar 24, as most clearly seen in Figures 4 and 6 may be pivoted between the offset end of the bar 20 and the outer surface 25 of the side rail 13, the pivot for the auxiliary bar being designated by the numeral 25. A pin 26 extends inwardly from the end of the auxiliary bar 24 to be slidably engaged with an elongated slot 27 provided in the side rail of the mattress supporting structure 30 so that the auxiliary bar 24 is caused to move toward or away from the free end of a supporting member 17 during pivotal movement of the bar 20. The free end 28 of the auxiliary bar is inclined upwardly and inwardly of the crib or cot so that when the bar 20 is swung downwardly the end 22 of the bar 20 and the end 28 of the auxiliary bar will abut with the free ends of the arms 18 constituting a part of the supporting 35 members 17, thereby causing the pins carried by the arms to abut with the outer ends of the slots 19. The bar 20 and auxiliary bar will then parallel the side rails of the mattress supporting structure and retain 40 these bars in contact with the supporting members. A catch 29 is pivoted to the side rail of the mattress structure adjacent the bar 20 carrying the auxiliary bar, so that the latch may swing over the longitudinal 45 edge of this end of the bar 20 to lock the same against upward swinging movement. The pins which are slidably associated with the slots have heads provided thereon to prevent their displacement or disengagement from their respective slots.

The head and foot members or pieces 30 are of identically the same construction and each include end vertical posts 31, the lower ends of which are secured to the arms of the 50 supporting members which are pivotally connected to the longitudinally extending bars 10 of the supporting frame. Due to this fact, it will be obvious that the head and foot members swing inwardly of the crib 55 when being disposed in a closed position.

It will of course be understood that the posts 31 of the head and foot members may be pivotally connected to the side bars 10 of the supporting frame at the point where the supporting members 17 are connected therewith and thus the arms 18 of these supporting members may be carried by the posts 31.

The side members 32 of the crib each consists of longitudinally extending upper and lower parallel rails 33 and 34 respectively 75 which are held in spaced relation by the vertical rods 35. In order that these side members may be pivotally connected to the mattress supporting structure, a pair of hinge members 36 are secured to each longitudinally extending rail 16 of the mattress supporting structure, and each hinged member consists of a strip of metal bent to provide an L-shaped loop as clearly shown in Figure 8. This loop provides members having L-shaped slots therein, and the lower longitudinal rail 34 of the side 32 operates within the L-shaped slot or loop 37. As clearly seen in Figure 8, the horizontal portion 38 of the loop extends laterally of the 80 crib so that when it is desired to swing a side member outwardly of the crib, it is pulled outwardly into the horizontal portion of the loop 37 so that it may swing clear of the bar 20 and other parts of the cot or crib which are arranged upon the side thereof. However, when it is desired to fold or collapse the sides of the crib, they are moved inwardly and downwardly of the loop 37 to be arranged in a position as shown in 100 dotted lines in Figure 8 so that the sides may be swung inwardly to be arranged upon the mattress supporting structure.

The upper rails 33 of the side members are tubular and mounted for sliding movement therein are opposed rods 39 the outer ends of which are adapted to be normally projected beyond the ends of the rail to fit in socket members 40 secured to the head and foot members for retaining the sides 110 in a position to enclose or surround the occupant of the crib. These two latch rods are urged in opposite directions by a coiled spring 41 interposed therebetween in the top rail 33 of each side member. Each latch rod at its inner end is provided with a depending grip 42 extending through a slot 43 in the lower portion of the tubular rail 33 whereby these latch rods may be manually controlled.

Assuming that the crib is in an open position as shown in Figure 1 and it is desired to collapse the same, the finger grips 42 are moved toward each other to disengage the exposed ends of the latch rods 39 from the sockets 40. The side members 32 are then swung inwardly of the crib to be arranged on top of the mattress supporting structure.

To permit the mattress supporting structure to move downwardly within the con- 130

fines of the supporting frame, the latches 29 are swung to disengage from the bars 20. Pressure is then exerted upon the mattress supporting structure to cause the inclined ends 22 and 28 of the bars 20 and 24 respectively to move downwardly out of engagement with the ends of the arms 18 of the supporting members 17. The head and foot members 30 will then swing inwardly of the crib causing the pins 18' of the supporting members 17 to move inwardly of the slot 19, then as the mattress supporting structure is moved farther downwardly within the confines of the supporting structure, these pins will move outwardly of their respective slots. When the mattress supporting structure is arranged in a collapsed position, it is supported by a longitudinally extending bar 43 extending the full length of the crib and having its ends bent as at 44 to extend vertically when the crib is in an open position. The extremities of the bar 43 terminate in L-shaped configurations one arm 45 of each being adjustably associated with the end rails 14 of the mattress supporting structure, by the provision of pins 46 carried by the arms 45 and being slidably mounted in slots 47 provided in the end rails of the mattress supporting structure. The other arms 48 of the angular ends of the bar 43 are pivotally connected as at 49 to the uppermost cross bar 11 of the supporting frame. Consequently, it will be seen that when the mattress supporting structure is in its lowermost position within the confines of the supporting frame, that the arm 45 of the bar 43 will be disposed in a vertical position that the pin 46 carried by this arm will engage the upper longitudinal edge of its respective slot 47 in the end rail 14 to support the mattress supporting structure. The bar 43 also serves the purpose of causing both ends of the mattress supporting structure to elevate simultaneously when either the head member or foot member is raised.

The foregoing description and the accompanying drawings have reference to the preferred or approved embodiment of our invention. It is to be understood however that such changes may be made in construction and arrangement of parts, materials, dimensions, etc., as may prove expedient and fall within the scope of the appended claims.

Having thus fully described our invention what we claim as new and desire to secure by Letters Patent is:—

60 1. A collapsible cot or crib comprising a supporting frame, a vertically movable mattress supporting structure adapted to be arranged within the supporting frame, supporting means pivoted to the frame and adjustably associated with the mattress sup-

porting structure, said members movable toward each other, and retaining means including a pivoted bar having inclined ends abutting the ends of said members for forcing the same in opposite directions and retaining the cot in an open position. 70

2. A collapsible cot or crib comprising a supporting frame, a vertically movable mattress supporting structure adapted to be arranged within the supporting frame, supporting members pivoted to the frame and adjustably associated with the mattress supporting structure, said members movable toward each other, and retaining means including a pivoted bar having one end abutting one of said members, and an auxiliary bar pivotally mounted and slidably associated with the mattress supporting structure to abut the other member for retaining the cot in an open position. 75

3. A collapsible cot or crib comprising a supporting frame, a vertically movable mattress supporting structure adapted to be arranged within the supporting frame, supporting members pivoted to the frame and adjustably associated with the mattress supporting structure, said members movable toward each other, retaining means including a pivoted bar abutting the ends of said members, and means for engagement with said bar for retaining the same in set position. 80

4. A collapsible cot or crib comprising a frame, including head and foot members, hinge members secured to said frame and each having an L-shaped slot therein, and side members hingedly mounted in said hinge members and movable inwardly and outwardly of the frame. 100

5. A collapsible cot or crib comprising a supporting frame, a vertically movable mattress supporting structure adapted to be arranged within the frame when in a collapsed position, and a member extending the full length of the cot and having its extremities adjustably and pivotally associated with both ends of the mattress supporting structure and pivotally connected to said frame. 105

6. A collapsible crib comprising a supporting frame, a vertically movable mattress supporting structure, supporting members pivoted to the frame and the mattress supporting structure, and retaining means including a bar having a break joint therein and adapted to abut said members and retain the crib in open position. 110

7. A collapsible cot comprising a supporting frame, a vertically movable mattress supporting structure associated therewith, head and foot pieces pivoted to the ends of the supporting frame, connections between the head and foot pieces and the mattress supporting structure for raising and lowering the same, and a bar extending from one 125

130

end of the mattress supporting structure to the other end and adjustably connected therewith, said bar having angularly disposed ends for connection with the supporting frame.

8. A collapsible cot comprising a supporting frame, a vertically movable mattress supporting structure, head and foot pieces pivoted to the ends of the supporting frame, 10 connections between the head and foot pieces and the mattress supporting structure for raising and lowering the latter, a bar extending from one end of the mattress supporting structure to the other end thereof and disposed beneath the same, the ends of said bar comprising laterally projecting substantially L-shaped terminals, the arms of which are of different lengths and disposed exteriorly of the mattress supporting structure, the horizontal arm of each L-shaped terminal being adjustably associated with the mattress supporting structure, and the longest arm of each L-shaped terminal being pivotally connected to the supporting frame 20 off center.

9. A crib comprising a supporting frame

including a side rail, L-shaped loops secured thereto and being disposed in inverted position whereby the horizontal arms thereof project laterally of said rail, and a side piece 30 for the crib associated with said L-shaped loops whereby said side piece may be moved outwardly of the crib.

10. A collapsible crib comprising a supporting frame, a vertically movable mattress 35 supporting structure adapted to be arranged within the supporting frame, supporting members pivoted to the frame and movably associated with the mattress supporting structure, said members being movable toward each other, and retaining means arranged between the members and abutting the ends of said members for retaining the crib in an open position.

In testimony whereof we affix our signatures in presence of two witnesses. 45
